Primary Examiner — Darcey E Gottschalk(74) *Attorney, Agent, or Firm* — Eckert Seamans Cherin & Mellott, LLC(57) **CLAIM**

The ornamental design for a ring pull tab, as shown and described.

DESCRIPTION

FIG. 1 is a top isometric view of the ring pull tab;
 FIG. 2 is another top isometric view of the ring pull tab;
 FIG. 3 is a bottom isometric view of the ring pull tab;
 FIG. 4 is another bottom isometric view of the ring pull tab;
 FIG. 5 is a top plan view of the ring pull tab;
 FIG. 6 is a bottom plan view of the ring pull tab;
 FIG. 7 is a side elevation view of the ring pull tab;
 FIG. 8 is a front elevation view of the ring pull tab;
 FIG. 9 is a back elevation view of the ring pull tab; and,
 FIG. 10 is a section view of the ring pull tab taken in the direction of line 10-10 of FIG. 5.
 In FIG. 5, the broken line arrows represent a sectional designation that forms no part of the claimed design.
